(57) **CLAIM**

I claim the ornamental design for a wall, as shown and described.

DESCRIPTION

FIG. 1 is an isometric view of a wall showing my new design;

FIG. 2 is a cross-sectional view taken on line 2-2 on FIG. 7; FIG. 3 is a cross-sectional view taken on line 3-3 on FIG. 7; FIG. 4 is an isometric view of one of the wall supports seen on FIG. 1;

FIG. 5 is a cross-sectional view taken along 5-5;

FIG. 6 depicts an enlarged view taken from FIG. 3; and, FIG. 7 is another isometric view showing the wall supports in alternate positions.

The dot-dot-dash broken line on the wall on FIGS. 1, 2 and 7 depict a symbolic break in the wall's width and height. The appearance of any portion of the article between the break lines forms no part of the claimed design.

The broken line circle on FIGS. 3 and 6 depicts the limits of the enlarged views.

The dot-dash broken lines on FIGS. 1 and 4 depict cross-sectional lines.

The evenly spaced broken lines represent non-claimed subject matter and form no part of the claimed design.
